SLUG CASTING MACHINE

Richard R. Mead, Queens Village, N. Y., assignor
to Mergenthaler Linotype Company, a corpora-
tion of New York

Application July 9, 1936, Serial No. 89,740

14 Claims. (Cl. 199—49)

This invention relates to slug casting machines of the general organization represented in U. S. Letters Patent to O. Mergenthaler, No. 436,532, wherein circulating matrices are released from a magazine in the order in which their characters are to appear in print, and then composed in line in a vertically movable assembler. After composition of the line, the assembler is raised and the line transferred therefrom into a vertically movable transporter, or so-called "first elevator", which thereupon descends to position the line between a pair of vise jaws which clamp and hold the line in front of a mold for the casting of the slug. After the slug casting operation, the transporter rises to its uppermost level and the matrices are transferred to a so-called "second elevator" for delivery to the distributing mechanism, by which they are separated and returned to the magazine whence they started.

When received by the first elevator, a matrix line is confined endwise between a so-called "line stop" carried by the first elevator, and a pair of retaining pawls permanently located at the receiving end of the elevator, the line stop being adapted and arranged to prevent twisting or displacement of the leading matrix in the line and the retaining pawls being adapted and arranged to prevent twisting or displacement of the last or terminal matrix in the line. For regular or ordinary classes of work wherein the vise jaws stand apart from one another a selected distance determined by setting the left hand jaw at the desired line measure, it is generally sufficient that the line stop engage the leading or foremost matrix of the line in the ordinary way, the operator in such case usually pushing the line stop into contact with the leading or foremost matrix in the first line of the measure being set and the stop ordinarily remaining in such position, due to its frictional engagement with the jaws of the line transporter, until the vise jaws are reset for a line of different measure at which time the line stop is again pushed by the operator into contact with the leading or foremost matrix in the first line of the new measure. However, in machines of this class which are equipped with means for moving one of the vise jaws as, for example, the right hand jaw, from its normal or line receiving position toward the other vise jaw to make a cast from a matrix line short of the measure for which the vise jaws are set, which operation is generally known as quadding, the line stop is automatically returned to the right each time a line is removed from the line transporter to insure support for the leading or foremost matrix in the

line thereafter assembled, regardless of its length. In the operation of machines so equipped, however, extreme care must be exercised to make certain that the line stop is not returned too far to the right in the transporter, otherwise it will strike the bottom face of the intermediate transfer channel during the descent of the line transporter from its line transfer position to its normal or line receiving position. Furthermore, when the line stop employed is of the usual U-shaped kind which is retained in position in the line transporter by friction developed only by the application of a horizontally disposed force, as for example, that created by the spreading of its legs into engagement with the walls of the transporter, its resistance to movement in the transporter is frequently insufficient to retain it against overthrow since the line, when pushed by the moving vise jaw, exerts a sharp propelling influence, and when the line stop is so overthrown, it, in addition to being carried out of its intended supporting relationship with the leading or foremost matrix in the line, is frequently carried over the left hand vise locking stud with the result that it is ruined by the stud when the line transporter thereafter descended from its normal or line receiving position to its casting position.

The primary object of the present invention is to provide a novel and improved line stop for the line transporter, or so-called first elevator, of typographical machines of the class referred to whereby overthrow of the line stop is prevented. Another object of the present invention is to provide such machines with novel and improved means for automatically returning the line stop to its right-hand matrix supporting position in the line transporter each time a line is transferred out of the line transporter into the intermediate line transfer channel.

To these and other ends, the invention consists in certain improvements and combinations and arrangements of parts all as will be herein-after more fully described, the features of novelty being pointed out particularly in the claims at the end of this specification.

In the accompanying drawings:

Fig. 1 is a front elevational view of a portion of a slug-casting machine embodying the features of the present invention;

Fig. 2 is an enlarged elevational view, with portions broken away, of the line transfer slide used to convey the matrices and spacebands from the line transporter into the intermediate line delivery channel;

Fig. 3 is an end view showing the relationship

between the line transfer slide and the line transporter;

Fig. 4 is a detailed vertical section showing the improved line stop positioned in the line transporter;

Fig. 5 is a plan view of the improved line stop; and

Fig. 6 is a side view of the improved line stop.

In the usual operation of the slug casting machine, which is partly shown in the drawings, matrices and spacebands are delivered from their places of storage in the machine by the manipulation of a keyboard (not shown) and are composed in line in the usual manner in an assembling elevator 10. After the line has been composed therein, the assembling elevator 10 is raised to position the line between a pair of depending fingers 11 and 12 of a line delivery slide 13, which thereupon transfers the line through an intermediate line delivery channel 14 into a vertically movable line transporter or first elevator 15. As the delivery slide 13 banks against a fixed stop screw 16, which limits the movement of its active stroke, the composed line will be located in the transporter 15 as indicated by the dotted lines in Fig. 1, where it is restrained against endwise displacement by a yielding line stop 17 and a pair of resilient pawls (not shown). The yielding line stop, except for changes subsequently to be described, comprises, as usual, a pair of L-shaped slide bars 18 and 19 which are connected together at one end by a connecting member 20 and these slide bars, which extend in parallelism, are spaced to slide in frictional engagement in L-shaped matrix supporting channels 21 and 22 in the front and back jaws 23 and 24 respectively of the line transporter 15. These slide bars extend into the line transporter from the left hand side thereof and their right hand ends form abutments against which the leading or foremost matrix in the line abuts when the line is positioned in the line transporter. The resilient pawls are permanently located at the receiving end of the transporter 15 and they are adapted and arranged to grip or snap in behind the last or terminal matrix as the line comes to rest. After the composed line has been transferred therein the line transporter 15 descends to the casting position where the composed line is positioned between a pair of vise jaws 25 and 26 which are aligned with the end walls of the mold slot and give to the line the required endwise support during the casting operation. After the slug is cast, the pressure on the vise jaws 25 and 26 is released and the line transporter 15 rises to its line transfer position, the line stop and the pawls meanwhile acting to prevent displacement of the matrices at the opposite ends of the line. As the line transporter 15 reaches its line transfer position, a reciprocating line transfer slide 27 positioned in a guide 28 in the machine frame operates under the influence of a line transfer slide lever 29 to remove the line from the line transporter 15 to the usual intermediate line transfer channel 30 from which the matrices are removed and conveyed to the matrix distributing mechanism which returns them to their usual place of storage and through which the spacebands are carried by the space band pawl 31 to their usual place of storage. After removal of the line from the line transporter 15 the latter descends in the usual manner to its normal or line receiving position.

75 In the usual operation of the machine, as de-

scribed above, it is generally sufficient that the line stop 17 engage the leading or foremost matrix in the line in the ordinary way, the operator in such case usually pushing the line stop 17 inwardly until the right hand ends of the slide bars 18 and 19 engage the leading or foremost matrix in the first line of the measure for which the machine is set and the stop ordinarily remaining in this position, due to its frictional engagement with the walls of the transporter, until 10 the vise jaws 25 and 26 are reset for a line of a different measure at which time the line stop is again pushed into engagement with the leading or foremost matrix in the first line of the new measure. In other classes of work, however, involving the use of quadding devices, such as those disclosed in U. S. Letters Patent to F. C. Frolander No. 1,949,302 wherein the right hand vise jaw 25 is moved inwardly from its normal line receiving position toward the left hand vise jaw 26 to confine the composed line which is shorter than the distance between the jaws for which the machine is set, it is common practice to return the line stop 17 to the right adjacent the line retaining pawls each time a composed line is transferred from the line transporter 15 to insure support for the leading or foremost matrix in the line thereafter assembled regardless of its length. In the event the line thereafter assembled is short of the measure for which the vise jaws 25 and 26 are set, and the right hand jaw 25 is moved to the left to close the line against the left hand jaw 26, the line stop 17 is pushed to the left through the line transporter 15 in supporting relationship with the leading or foremost matrix in the line. In these machines, however, the closing movement of the right hand jaw 25 and the consequent shift of the composed line to the left is sudden and unless means are provided to prevent it the line stop 17, when the composed line is suddenly brought to a halt against the left hand vise jaw 26, is quite likely to be propelled beyond its supporting relationship with the leading or foremost matrix in the line, even to the extent of being carried over the left hand vise clamping stud 32 where it would be ruined by the latter when the line transporter 15 descended to casting position.

In accordance with the present invention propulsion of the line stop beyond its supporting relationship with the leading or foremost matrix in the line as the line is moved against the left hand jaw 26 under the influence of the right hand jaw 25 is prevented by increasing the frictional resistance to movement of the line stop 17 in the line transporter 15, and to this end a plurality of resilient members are adapted and arranged to press the slide bars 18 and 19 of the line stop 17 into frictional engagement with the L-shaped matrix grooves 21 and 22 in the line transporter 15 in a direction other than horizontal to its line of travel in the line transporter. In the embodiment of the invention illustrated the resilient members comprise flat springs 33 positioned, as by pins 34, in recesses 35 cut in the horizontally disposed ledge of the L-shaped slide bars of the line stop. As thus positioned these flat springs 33 exert vertical forces which tend to resist the movement of the line stop 17 through the matrix supporting grooves 21 and 22 in the line transporter 15, and these forces when added to the usual horizontally disposed forces which are obtained, for example, by spreading the slide bars until their side faces frictionally engage the 75

side walls of the grooves 21 and 22 are sufficient to prevent the line stop 17 from being propelled beyond its supporting relationship with the leading or foremost matrix in the line as the line is moved to the left by the closing movement of the right hand jaw 25.

The right hand end of the inner slide bar 18 of the improved line stop is also provided with a stud 36 which is adapted and arranged to engage a stop member 37 positioned at the left hand end of the space band slide groove 38 in the back jaw 24 of the line transporter 15 when the line stop 17 is moved to the left a predetermined distance, this arrangement being provided to prevent the line stop 17 from being moved accidentally to the left to a position where it would engage the left hand vise clamping stud 32 during its travel to or from the casting position.

After the casting operation, the line transporter 15 moves upwardly to its line transfer position where the line is transferred, as usual, to the intermediate line transfer channel 30, and to insure the return of the improved line stop to the right the line transfer slide 27 is provided with a plate 39 having a finger 40 which extends outwardly therefrom and which is adapted and arranged to engage the left hand end of the line stop 17 when it is moved to the right in the usual manner by the line transfer lever 29. The finger 40 is so positioned that when the line is transferred to the intermediate channel 30 the right hand ends of the slide bars are positioned adjacent the retaining pawls in the line transporter 15, and to prevent the line stop 17 from being carried to the right beyond this position the transporter jaw separating block 41 is provided with a stop pin 42 which extends downwardly therefrom and which engages the connecting member 20 when the line stop 17 has been moved to this position.

While the improved line stop has been described as being of particular advantage in connection with slug casting machines equipped with quadding and centering devices it is evident that it is also of advantage in connection with machines not so equipped, since it eliminates any possibility of the line stop from being jarred out of supporting relationship with the leading or foremost matrix in the line when the line is left hanging in the jaws of the transporter while the transporter ascends from the line casting to the line transfer position.

Also, it is to be understood that the invention has been shown merely in preferred form and that many changes and variations may be made therein and in its mode of operation which will still be comprised within its spirit. In consequence, the invention is not to be limited to any specific form or embodiment except insofar as such limitations are specified in the claims.

Having thus described my invention, I claim:

1. A line stop for the first elevator or line transporter of a typographical machine comprising spaced slide bars, and a friction creating member fixedly secured to one of said bars.
2. A line stop for the first elevator or line transporter of a typographical machine comprising spaced slide bars, and friction creating springs fixedly secured to said bars.
3. A line stop for the first elevator or line transporter of a typographical machine comprising L-shaped slide bars, and friction creating members fixedly secured to the horizontally disposed ledges of said bars.
4. A line stop for the first elevator or line transporter of a typographical machine comprising L-shaped slide bars, and friction creating springs fixedly secured to the horizontally disposed ledges of said bars.

5. In a typographical machine having a transporter adapted to receive an assembled line of matrices, a line stop positioned in the transporter in the path of an incoming line, and means fixedly secured to the line stop and adapted to resist the movement of the line stop through the transporter.

6. In a typographical machine having a transporter adapted to receive an assembled line of matrices, a line stop positioned in the transporter in the path of an incoming line, and springs fixedly secured to the line stop and adapted to resist the movement of the line stop through the transporter.

7. In a typographical machine having a transporter adapted to receive an assembled line of matrices, a line stop frictionally positioned in the transporter in the path of an incoming line, and means for increasing the frictional resistance to movement of said stop through said transporter other than by the application of a horizontally disposed force.

8. In a typographical machine having a transporter adapted to receive an assembled line of matrices, a line stop frictionally positioned in the transporter in the path of an incoming line, and a resilient member adapted to apply a vertical force on said stop to increase its frictional resistance to movement through the transporter.

9. In a typographical machine having a transporter adapted to receive an assembled line of matrices, an L-shaped slide bar frictionally positioned in an L-shaped matrix supporting groove in said transporter and in the path of an incoming line, and means for applying a vertical force on the horizontally disposed ledge of said bar to increase the frictional resistance to movement of said bar through said transporter.

10. In a typographical machine having a transporter adapted for the reception of an assembled line, L-shaped slide bars frictionally positioned in L-shaped matrix supporting grooves in said transporter and in the path of an incoming line, and springs adapted and arranged to apply a vertical force on the slide bars to increase the frictional resistance to movement of said bars through said transporter.

11. In a typographical machine having a transporter adapted to receive an assembled line of matrices, a slide bar positioned in the transporter in the path of an incoming line and extending in two planes, and means for applying a friction creating force between said bar and said transporter perpendicularly to each plane.

12. In a typographical machine having a transporter adapted to receive an assembled line of matrices, a U-shaped line stop positioned in the transporter in the path of an incoming line and comprising slide bars which extend in both a horizontal and a vertical plane, and means for applying a friction creating force between said bar and said transporter perpendicularly to each plane.

13. In a typographical machine, the combination of a line transporter having jaws to support an assembled line, means for delivering an assembled line of matrices into said transporter, a line stop mounted in the transporter in the path of the incoming line, means including a vertically applied force for resisting the advance of said stop through said transporter, and means for automatically returning said stop to its initial

position as the line is removed from the transporter.

14. In a typographical machine having a line transporter for conveying composed lines to and from casting position and a pair of vise jaws adapted to be set for different line measures, at least one of said jaws being movable for clamping short lines in casting position, a line stop

carried by the transporter and arranged to be shifted by movement of a line by the movable jaw toward the other jaw, and means including a vertically applied force for preventing overthrow of the line stop when the movement of a line is halted.

RICHARD R. MEAD.
